UNITED STATES PATENT OFFICE.

CHARLES L. MOREHOUSE, OF BROOKLYN, NEW YORK.

BOTTLE-STOPPER.

SPECIFICATION forming part of Letters Patent No. 310,304, dated January 6, 1885.

Application filed June 14, 1884. (No model.)

To all whom it may concern:

Be it known that I, CHARLES L. MOREHOUSE, of Brooklyn, Kings county, New York, have invented a new and Improved 5 Bottle-Stopper, of which the following is a full, clear, and exact description.

The object of my invention is to provide a new and improved bottle-stopper which is simple in construction and closes the bottle 10 very tightly, and is strong and durable.

The invention consists in parts and details and combinations of the same, as will be fully set forth hereinafter and claimed.

Reference is to be had to the accompanying 15 drawings, forming part of this specification, in which similar letters of reference indicate corresponding parts in both figures.

Figure 1 is a side view of a bottle provided 20 with my improved bottle-stopper. Fig. 2 is a longitudinal sectional view of the same.

An open or split-spring-ring, A, or any other suitable ring, collar, band, or like device, is held on the neck of a bottle, B, directly below the head C, and on the said ring or collar A 25 the ends of two opposite arms, D, are pivoted, which project from an internally screw-threaded ring, E, in which a screw plug or cap, F, is screwed, which contains a rubber plug, G, held in the cap in some suitable manner, and provided at or near its bottom edge with an annular projection or shoulder, H. At the lower 30 edge of the ring E the threads are cut out to form an annular recess and shoulder or offset, J, on the inner surface of the ring E. The cap F is provided with a milled head, K, or with any other suitable head or top. The rubber plug can be arranged on the lower end 35 of the plug or cap F, and can be arranged to turn on a central pin of the plug or cap F.

40 The stopper operates as follows: The ring E is swung over the head C, and the cap or plug F is screwed down until the bottom or lower

end surface of the rubber plug G is pressed firmly on the top edge of the head C, thus closing the same air-tight. If the bottle is to 45 be opened, the plug or cap F is unscrewed until the bottom edge of the plug G can clear the upper edge of the head C, and then the stopper is swung down, as shown in Fig. 1. When the cap F is unscrewed as far as possible, the 50 annular projection or shoulder H of the plug G rests against the shoulder J of the ring E and prevents removing the cap F or stopper entirely from the ring E, thereby preventing the loss of the cap F or stopper. 55

The stoppers may be made in different sizes, and the shape of the rubber plug G may be varied according to the shape of the neck or head of the bottle.

The stopper does not occupy much space, 60 and is not apt to become loosened, as the entire side surface of the stopper is threaded and in contact with the threaded surface of the ring E.

The above-described stopper can be used 65 for fruit-jars, cans, or other vessels.

The ring E may be screw-threaded externally and the cap screw-threaded internally; but I prefer to provide the ring E with an internal screw-thread and the cap with an external screw-thread. 70

Having thus described my invention, I claim as new and desire to secure by Letters Patent—

In a bottle-stopper, the combination, with the internally screw-threaded ring E, having 75 arms D, and an offset, J, of the screw-plug F and elastic plug G, held in the ring E, and provided with a projection, offset, or shoulder, H, substantially as herein shown and described.

CHARLES L. MOREHOUSE.
